UNITED STATES PATENT OFFICE.

ALBERT T. HANSON, OF SEATTLE, WASHINGTON.

PNEUMATIC ARCH SUPPORT.

Application filed December 28, 1921. Serial No. 525,388.

To all whom it may concern:

Be it known that I, ALBERT T. HANSON, a citizen of the United States, residing at Seattle, in the county of King and State of Washington, have invented certain new and useful Improvements in Pneumatic Arch Supports, of which the following is a specification, reference being had to the accompanying drawings.

10 This invention relates to arch supports and has for its object to provide an arch support capable of being arranged to suit any arch whether normal or disfigured.

15 Another object of the invention is to provide a support of this character wherein no steel or metal is used to support the arch.

20 Another object of the invention is to provide a support of this character including an insole to which a pneumatic pad is connected, the pad being provided with means for regulating the size of the same to suit the arch of the user.

25 Another object of the invention is to provide an arch support of this character including an insole and a pneumatic pad, said pad extending longitudinally and laterally of the insole and terminating adjacent the end portions of the insole.

30 A further object of the invention is to provide an arch support of this character including a pneumatic pad having a tube for inflating the same, the tube being provided with means for closing the same to

35 prevent leakage of air, said means being substantially embedded in the insole to render the device compact.

With these and other objects in view, the invention consists in the improved construction and arrangement of parts to be hereinafter more particularly described, fully claimed and illustrated in the accompanying drawings, in which:

40 Figure 1 is a side elevation showing the pad of the arch inflated and ready for use;

Figure 2 shows the pad deflated with the fastening device partially removed;

Figure 3 is a bottom plan view of the arch;

45 Figure 4 is a transverse sectional view showing the recess and slot for the fastener;

Figure 5 is a detailed perspective view of the fastener.

50 Referring to the drawings, 5 designates an insole, the end portion 6 of said insole

being rounded to conform to the curvature of the heel of the shoe, while the end portion 7 is substantially straight. Secured to one face of the insole and coinciding with the end portion 7 thereof is a lamination 8 of material such as leather, the inner edge of the lamination being substantially curved as at 9, a slot 10 being provided at the intermediate portion of said lamination, said slot extending through the inner end thereof, the purpose of which will be hereinafter described.

55 The intermediate portion of the lamination immediately above the slot is removed to provide a recess 10^a which extends from the outer to the inner end of said lamination, while secured to the outer face of the lamination and extending over one end portion of the recess 10^a is a sheet of material 11, said sheet cooperating with the end portion of the recess to provide a pocket.

60 The opposite end portion 7 of the insole is tapered so as to lie perfectly flat when within the shoe. A strip of material 12 is secured to the end portion 7 inwardly of the extremity of said end portion, while extending over said strip and substantially merging with the extremity of said end portion is a lamination of material 13. By the use of the laminations at each end of the insole a recess is substantially provided between said lamination, said recess extending laterally of the insole.

65 In connection with the insole 5, a pneumatic pad 14 is provided, said pad when deflated being adapted to lie flush with the lower surface of the laminations at each end of the insole so that it substantially forms a part of the insole. The pad consists of two laminations of material, such as rubber, which are secured at their edges to each other. The inner lamination of the pad is longer than the outer lamination so as to provide a projection at the end portion 15 of the pad, adapted to be engaged by the laminations at the end portion 17 to assist in securing the pad to the insole. The opposite end portion 16 of the pad is cut to conform to the curvature of the inner end portion of the lamination 8. A relatively small tube 17 is connected to the end portion 16 of the pad, said tube being adapted to enter the pocket provided by the cooperation of the slot 10 with the insole, so as to eliminate the possibility of projections when the support is in use. The pneumatic

pad is secured at each of its ends 15 and 16 to the insole and to the adjacent portions of the laminations at each end of the insole, the longitudinal edges of the pad being free 5 with respect to the longitudinal edges of the insole, to prevent interference with the self-adjustment of the arch support when in use.

In order to prevent the escape of air after the pneumatic pad has been inflated, a novel 10 form of fastening means is provided, said means comprising a strip of material 18 having a slot 19 in one end portion thereof, and a finger or lip 20 struck from the opposite end portion and extending toward 15 the slot. In connection with the strip 18, a strip 21 is used, said strip having recesses 22 provided adjacent one end portion thereof to form a T-shaped head 23, the strip 22 being shorter than the strip 18. In the application 20 of the fastening means, the T-shaped head 23 is inserted through the slot 19. The strip 21 is then turned so as to position the neck formed by the recesses 22 within the slot in such a way that the strips 18 and 21 25 will be disposed in parallel relation. The opposite end 24 of the strip 21 is adapted to be disposed beneath the finger or lip 20 so as to firmly clamp said strips to each other. It will be noted that the end portion of the 30 strip 18 provided with the slot 19 is slightly sprung so as to cooperate with the strip 21 to produce a clamping action.

In the use of the device, the user inflates the pad 14 by means of the tube 17. The 35 tube is then passed through the slot 19 in advance of the neck formed by the recesses 22 so as to dispose the tube between the strips 18 and 21. The end portion 24 of the strip 21 is then inserted beneath the finger or lip 20 so as to clamp the end of the tube between 40 said plates and thereby prevent the escape of air. The fastener or valve is then in-

serted in the recess 10 with its end inserted in the pocket formed through the cooperation of the end of the recess and the sheet 45 11, thereby disposing the tube, as well as the fastener or valve member flush with the lower surface of the lamination 8.

From the foregoing it will be readily seen that this invention provides a novel form of 50 arch support which will automatically fit any arch, whether normal, disfigured or out of shape, or any last of shoe by simply regulating the amount of air within the pad 14. In addition to this, the device will protect 55 the arch of the user from cold or damp in view of the air space under the arch. It will also protect the arch of the wearer from the heat of the streets in hot weather, as the air space under the entire arch and foot, as well 60 as the air within the pneumatic pad will stay at blood temperature. In addition to this, in view of the novel valve or fastening member, the amount of air can be quickly 65 regulated, and no special means is necessary in order to position or hold the arch support within the shoe.

What is claimed is:—

An arch support comprising an insole, a 70 lamination of material carried by each end portion of said insole, said laminations projecting from one face of the insole, one of said laminations having a recess and a pocket disposed at one end of said recess, a 75 pneumatic pad secured to the insole between said laminations, a tube extending from said pad, and means engaged with said tube to prevent deflation of the pad, said means being disposed within the recess and the pocket.

In testimony whereof I hereunto affix my signature.

ALBERT T. HANSON.
